CLAIM

The ornamental design for a hinge component extrusion, as shown and described.

DESCRIPTION

FIG. 1 is a cross sectional view of our new design, taken along line 1—1 of FIG. 3;

FIG. 2 is a top front perspective view of our design, the fragmentarily shown far end thereof continuing for an indeterminate length within the area bounded by the broken lines; and,

FIG. 3 is a fragmentary rear elevational view of our design.
